UNITED STATES PATENT OFFICE.

FREDERICK W. VICKERY, OF LONDON, ENGLAND, ASSIGNOR TO VICKERY LIMITED,
OF BOSTON, MASSACHUSETTS, A CORPORATION OF MASSACHUSETTS.

FELT-RECONDITIONING APPARATUS.

Application filed February 8, 1924. Serial No. 691,534.

To all whom it may concern:

Be it known that I, FREDERICK W. VICKERY, a subject of the King of England, residing at London, England, have invented 5 new and useful Improvements in Felt-Reconditioning Apparatus, of which the following is a specification.

This invention relates to an apparatus for reconditioning the transporting felt belt of 10 paper making machines.

In paper making machines, the felt belt conveys the paper pulp in web form between 15 press rolls. These rolls press both the felt and the web of paper, squeezing out the water.

In paper machines of this class, after the felt belt has been used for a certain length of time it deteriorates, that is, the threads of the felt are pressed by the press rolls and 20 are caused to assume a flattened shape. This flattening of the threads of the belt closes the pores of the felt and interferes with the squeezing of the water by the press rolls out of the paper web and through the felt 25 belt. When this condition of affairs occurs, the character of the paper deteriorates. The deterioration of the felt belt is also partly due to dirt or other material which is left upon the felt belt by the paper web, but 30 this is not the principal difficulty leading to the above deterioration of the felt, and it is the main object of this invention to overcome the difficulty hereinbefore set forth, namely the deterioration of the felt belt by 35 the flattening of the threads and the consequent lateral spreading of the threads and filling up of the spaces or pores which would otherwise exist in the felt belt.

If the felt belt is not reconditioned, the 40 warps will return repeatedly to the press rolls in exactly the same relative positions, until all the elasticity is pressed out of them, and finally each thread takes a permanent set making a continuous impervious mat so

45 that the water cannot pass through the same. When this happens, the paper manufactured on the machine becomes what is known technically as "crushed" and it becomes necessary to stop the machine and install a 50 new felt belt in order to restore the machine to its normal operative condition or to stop the machine and recondition the belt.

In order to overcome the flattening, widening and matting of the threads of the 55 felt, this invention contemplates disturbing

this matted condition so as to restore the threads as far as possible to their original shape and position by causing them to change their positions relatively to each other so that they will not all constitute 60 flattened threads lying in a substantially horizontal plane.

In addition to the changing of the positions of the threads relatively to each other and thereby correcting the flattened shape 65 of the same, this invention contemplates removing the dirt from the felt belt, in other words, the invention contemplates cleaning the belt as well as reconditioning it with respect to the flattened threads thereof. 70

To these ends the apparatus of this invention contemplates employing a narrow jet 75 of water under pressure and directed against one face of the felt belt with sufficient force to cause the water to pass through the felt and preferably the water employed should be hot, and in order to secure this desirable condition of the water, the apparatus of this invention contemplates using a jet of steam in close proximity to the jet of water. 80

In order to assist in holding the belt in position to be operated upon by the jet of water, but principally for the purpose of drawing the water through the belt in the opposite direction to that in which it has been ejected from the ejecting port of the reconditioning device, a suction member is employed consisting of a suction box extending entirely across the width of the belt which is to be reconditioned and provided 85 with a suction port also extending entirely across said width. Suction is applied at the suction port which acting upon the belt in the opposite direction to the force of the jets of water and steam, causes the water to be sucked through the belt in the opposite direction to that in which it is supplied to the belt by the ejecting fluid port. 90

The reconditioning member with its ports and means for supplying fluid under pressure as hereinbefore set forth, is moved transversely of the felt belt with the ejecting port or ports in close proximity to one surface of said felt belt and is moved very slowly as compared with the speed of the belt which is being reconditioned, the distance traveled by the fluid ejecting port being approximately not greater than the distance across said port during a travel of the belt throughout its entire length. 100 105 110

It has been found that in order to prevent the threads of the felt belt from acquiring a permanent set it is necessary to disturb them very vigorously and it is not sufficient 5 in order to attain this result merely to force a jet of cleaning fluid through the felt, but if the fluid can be caused to return sharply upon itself, it will exert a twisting or curling effect upon the threads of the belt, 10 whereas a jet passing straight through the felt would merely thrust them aside.

The apparatus of this invention accomplishes this desirable result, that is, fluid preferably water, heated, is forced through 15 the belt in a limited area and is then drawn through the belt in the opposite direction by the suction device, and this causes a twisting or curling effect upon the threads which changes the relation of the threads to each 20 other and overcomes the flattened condition hereinbefore referred to and at the same time the felt will be cleansed thereby.

It will be understood that in order that the belt should be reconditioned and have 25 imparted to the threads thereof the twisting or curling effect hereinbefore referred to, that that portion of the belt which is being reconditioned must, during this reconditioning operation, be firmly held down 30 against the upper face of the reconditioning member by the suction, and in order that this should be carried into practical operation, therefore, the suction port must be located adjacent to the ejecting port and 35 preferably upon two sides thereof or entirely surrounding the same.

The invention consists in the improved method of reconditioning the felts of paper making machines and the apparatus for carrying said method into practical operation, all as hereinbefore set forth and particularly as pointed out in the claims.

Referring to the drawings:

Figure 1 is a plan view partly broken away and partly shown in section of an apparatus embodying one embodiment of my invention.

Fig. 2 is a sectional elevation taken on the line 2—2 of Fig. 1.

Fig. 3 is a perspective plan view of a portion of the apparatus of my invention.

Fig. 4 is a sectional elevation taken on the line 4—4 of Fig. 1.

Figs. 5 and 6 are enlarged sectional elevations taken on the line 5—5 of Fig. 1 showing the mechanism for reversing the feed of the reconditioning member in two positions.

Fig. 7 is a sectional elevation of another embodiment of my invention in which the reconditioning member is contained within the suction member.

Fig. 8 is a diagrammatic elevation as viewed from the right of Fig. 1 of a portion 65 of the felt reconditioning mechanism, the

transporting felt belt and mechanism adapted to move the felt belt and to actuate the reconditioning member.

Like numerals refer to like parts throughout the several views of the drawings.

In the drawings, referring to Figs. 1 to 6 inclusive, 15 and 16 are oppositely disposed side members of the frame of the apparatus connected together by a beam 14 which is of an inverted V shape in cross section. Upon the beam 14 is slidably mounted a reconditioning member 17. The reconditioning member 17 is provided with a top plate 18 upon which the felt belt 19 rests. Said top plate is provided with a fluid ejecting port 20 and a steam ejecting port 21. The port 20 is connected by a pipe 22 to a source of water supply under pressure and the port 21 is connected by a pipe 23 to a steam supply. A suction member 24 extends across the machine and is supported at its opposite ends upon the side members 15 and 16 of the frame. Said suction member is provided with a chamber 25 and with a suction port 26, the chamber 25 being connected by a pipe 27 with a suitable suction apparatus. It will be understood, therefore, that the suction member is stationary and that the port 26 extends across the entire width of the portion of the belt 19 to be reconditioned.

The reconditioning member 17 has a reciprocatory motion imparted thereto to carry the same entirely across while in contact with the surface of the belt 19 by a screw 28 which has screw-threaded engagement with said reconditioning member and is rotated by a pawl and ratchet mechanism which will now be described.

A shaft 32 is rotatably mounted in the frame of the machine and is provided at one end thereof with a crank arm 33 which is connected by a coil spring 34 to a stationary bracket 35. The opposite end of the shaft 32 has a segmental arm 36 fast thereto provided with a segmental slot 37.

Near each of its ends, the shaft 32 has cams 38 and 39 and the reconditioning member 17 is also provided with oppositely arranged cams 40. An eccentric 41 is rotatably mounted upon the frame of the machine, together with a sprocket wheel 42 which is fastened thereto. The sprocket wheel 42 is driven by a chain 43 see Fig. 8, from a sprocket 60 which is fastened to a shaft 61 to which is fastened one of the feed rolls 62 of a felt feeding mechanism ordinarily used and well known to those skilled in the art of paper making machines. The feed roll 62 co-operates with a feed roll 63 to feed the felt belt 19 in the direction of the arrows, see Fig. 8. The felt belt is guided by rolls 64, 65, 66, 67, 68 and 69.

The eccentric 41 is rotatably mounted in a sliding block 44, see Figs. 5 and 6, which in

turn, is slidably mounted in a rocker frame 45, the rocker frame 45 being pivoted at 46 to the frame of the machine. The rocker frame 45 has pivotally connected to it at 47 a pair of oppositely disposed pawls 48 and 49, having laterally extending pins 50 and 51 respectively.

Immediately disposed in the plane of the pawls 48 and 49 is a toothed wheel 52 which 10 is secured to the screw rod 28, and adjacent to the toothed wheel 52 and loosely mounted on the plain end of the screw 28 is a sector 53 which has pivotally connected to it at 54 a skeleton balance weight 55 15 which surrounds the end of the screw rod 28. The sector 53 is connected by a link 56 to the slotted segmental arm 36 of the shaft 32 by a pin 57 which projects into the segmental slot 37.

20 The operation of the screw rotating mechanism is as follows:—Assuming that the reconditioning member 17 be at one side of the machine and the reversing mechanism positioned as in Fig. 5 with the pawl 48 25 lifted by the sector 53 out of engagement with the teeth of the wheel 52; the sprocket wheel 42 is driven and the eccentric 41 will revolve, moving the block 44 up and down in the rocker frame 45, and at the 30 same time the rocker frame 45 will be rocked about its pivot 46 so that the pawl 49 will push the toothed wheel 52 the required distance and then return to engage the next tooth, and during the forward 35 movement of the pawl 49 the screw rod 28 will be rotated by reason of the toothed wheel 52, being fixed to it and this action continues until the reconditioning member 17 has been moved by the screw rod 28 along 40 the beam 14 entirely across the portion of the belt 19 which is being reconditioned, whereupon the cam 40 on the member 17 will engage the cam 38 on the shaft 32 and will rock the shaft 32 at the same time 45 putting tension on the spring 34, the slot 37 in the arm 36 riding over the pin 57 of the link 56 until the pin 57 arrives at the end of the slot 37, whereupon the anchorage of the spring 34 to the crank arm 50 33 will have passed the dead center line between the shaft 32 and the anchorage of the spring 34 to the bracket 35 and with the assistance of the cams 40 and 38, will rock the sector 53 to engage the pin 51 55 of the pawl 49 and lift the pawl 49 out of engagement with the toothed wheel 52, whereupon the travel of the reconditioning member 17 will be stopped.

During this movement of the sector 53, 60 the balance weight 55 will have swung across the vertical median plane of the sector 53 and said balance weight 55 will thereby assist in moving the sector 53 from the position illustrated in Fig. 5 to that illustrated in Fig. 6, the sector being retained

in the proper position by the inside edge of the balance weight on one side resting against a collar 58 on the screw rod 28.

During this movement of the sector 53, 70 the pawl 48 is released and engages the toothed wheel 52, and the continued rotation of the sprocket wheel 52 will now cause the rocker frame 45 to compel the pawl 48 to act upon the toothed wheel 52 and move it in the reverse direction to that 75 in which it has hitherto been moving, and thus reverse the movement of the screw rod 28, and at the end of the movement of the reconditioning member across the belt 19 in the opposite direction to that in which it has 80 been moved hitherto, the same reversing action, but in an opposite manner, with regard to the pawls 48 and 49, takes place and the rotation of the screw rod 28 is again reversed, causing the reconditioning member 85 17 to be moved across the belt in the same direction as first hereinbefore described.

The screw thread on the screw rod 28 has such a pitch and the mechanism by 90 which it is rotated bears such a relation to the mechanism which feeds the felt belt that the reconditioning member will move across the belt a distance not greater than the distance across the ejecting port 20 95 measured transversely of the belt 19, during a travel of the belt 19 throughout its entire length.

The reconditioning member 17 operates 100 on the face of the belt 19 as it passes over the top 18 of said reconditioning member on the return or bottom run of the belt. Consequently the felt belt can be changed as quickly and easily as if the reconditioning member were not installed or can be reconditioned without, in any way, interfering with the continuous operation of the paper making machine.

The face of the belt 19 contacts with 110 the upper face of the top 18 of the reconditioning member 17, water is forced through the pipe 22 out of the fluid ejecting port 20 and through the transporting felt belt 19 and is heated by means of steam from the steam pipe 23 and steam port 21. The hot water issues from the fluid ejecting port 20 in the form of a jet and is forced upwardly through the felt and is caused to turn sharply upon itself, and is drawn downwardly 115 through the felt by the suction from the suction port 26, and thus a twisting or curling effect will be exerted upon the threads of the felt. The belt is firmly held against the top 18 by the suction at the suction port 26.

The distance across the ejecting port referred to in the claims means the distance across the ejecting port measured in the direction of its travel or transversely of the 120 felt belt. The term "felt" used in connec- 130

- tion with the paper transporting belt is a technical term used in the paper manufacturing trade, but it is to be understood that this invention is not intended to be limited 5 to a transporting belt made of felt as a belt made of some fabric other than felt may be reconditioned and cleansed by the device of this invention without departing from the spirit of my invention.
- 10 The general operation of the apparatus hereinbefore described is as follows:—The belt 19 is fed in the direction of the arrow *a*, Figs. 1, 2 and 4. The reconditioning member is positioned at one side of the belt with 15 the fluid and steam ejecting ports immediately adjacent to one surface of the belt, suction is applied to the belt 19 at the suction port 26 through the pipe 27, water is forced through the fluid ejecting port 20 and steam is forced through the steam ejecting port 21 from the pipes 22 and 23 respectively. The hot water passes through the belt and upwardly above the belt. The reconditioning member is fed transversely of 20 the belt by the screw rod 28 as hereinbefore described at such a speed that the fluid ejecting port will not travel a greater distance than its width measured transversely of the belt during a travel of the belt 25 throughout its entire length. When the reconditioning member has traveled transversely of the belt until the fluid and steam ejecting ports have traveled entirely across the portion of the belt which is being reconditioned the direction of rotation of the screw rod 28 is reversed by the mechanism hereinbefore described and the reconditioning member then travels backwardly across the portion of the belt which is being reconditioned. 30 Hot water is forced upwardly through the belt from the ejecting port 20 and is drawn backwardly down through the belt by the suction at the suction port 26 thus disturbing the threads of the belt and 35 changing their location relatively to each other so as to open up spaces between the threads which formerly were flattened and in close relation to each other and also cleaning the belt.
- 40 While the apparatus hereinbefore described has embodied therein a port and means for supplying steam to heat the fluid or water, it is to be understood that my invention is not limited to this construction 45 as the apparatus is equally effective if hot water can be obtained and supplied to the fluid ejecting port, in which case the steam ejecting port and means for conveying steam thereto may be omitted.
- 50 In the embodiment of my invention hereinbefore described and illustrated in Figs. 1 to 6 inclusive, I have illustrated the traveling reconditioning member as located outside of the stationary suction member 24, but 55 in some classes of work and under certain

conditions it is preferable that the fluid ejecting port should be surrounded by the suction port, or in any event, that the suction port should be positioned on opposite sides of the fluid ejecting port and such a construction is illustrated in Fig. 7 wherein 70 17' is the reconditioning member slidably mounted upon a beam 14' which is of an inverted V shape in cross section.

The reconditioning member 17' has a 75 reciprocatory motion imparted thereto by a screw 28' by mechanism similar to that hereinbefore described whereby the reconditioning member 17 had reciprocatory motion imparted thereto. The reconditioning member 17' is provided with a fluid ejecting port 20' which projects through and is surrounded by a suction port 26' provided in a top plate 18' which extends across a suction member 24' provided with a chamber 25'. The suction member 24' extends across the machine and is supported at its opposite ends upon side members similar to the side members 15 and 16 illustrated in Fig. 1.

The fluid ejecting port 20' is connected by a pipe 22' to a source of water supply under pressure and the suction chamber 25' is connected by a pipe 27' with a suitable suction apparatus. A shaft 32' is rotatably mounted in the frame of the machine and is operated by mechanism similar to that illustrated and described as operating the shaft 32 in the embodiment of my invention illustrated in Figs. 1 to 6 inclusive.

The operation of this embodiment of my 100 invention is as follows:—The belt 19' is fed in the direction of the arrow *a'*, Fig. 7, along the upper face of the top plate 18', with the fluid port 20' and the suction ports 26' immediately therebeneath and adjacent 105 to the under surface of the belt. Suction is applied to the belt 19' at the suction ports 26' through the pipe 27' and chamber 25'. Water is forced through the fluid ejecting port 20' and passes through the belt and 110 upwardly above the belt 19'. The reconditioning member 17' is fed by the screw 28' transversely of the belt 19' and longitudinally within the suction chamber 25' by the screw rod 28' as hereinbefore described, 115 preferably at such a speed that the fluid ejecting port will not travel a greater distance than its width measured transversely of the belt during a travel of the belt throughout its entire length. When the 120 reconditioning member has traveled transversely of the belt until the fluid port 20' has traveled entirely across the portion of the belt which is being reconditioned, the direction of rotation of the screw rod 28' is 125 reversed by the mechanism hereinbefore described and the reconditioning member then travels backwardly across the portion of the belt which is being reconditioned. Hot water is forced upwardly through the 130

- belt from the ejecting port 20' and is drawn backwardly down through the belt by the suction at the suction ports 26', thus disturbing the threads of the belt and changing their locations relatively to each other so as to open up spaces between the threads which formerly were flattened and in close relation to each other and also cleaning the belt.
- 10 In a construction of this character the belt is held more firmly against the inner face of the reconditioning member and the reconditioning action will, therefore, be more efficiently carried out if a suction port 15 entirely surrounds the fluid ejecting port, or in any event is located upon opposite sides of the fluid ejecting port.
- While I have described in the foregoing specification and have set forth in many of 20 the claims a suction device for causing the water to return through the felt belt for reconditioning the same, I may, without departing from the spirit of this invention, cause the water to be returned through the 25 belt by the direct pressure of air, provided by means other than suction, as it is evident that instead of suction supplied by a suction port, located beneath the belt, pressure of air may be supplied above the belt 30 and thus drive the water downwardly through the belt and into the port, which I have referred to as a suction port, or the pressure of air may be applied to the upper surface of the belt, together with the 35 suction port and suction applied thereto, without departing from the spirit of my invention.
- I claim:
1. The method of reconditioning the transporting felt belts of paper making and similar machines which consists in forcing a jet of fluid through a felt belt while the belt is moving longitudinally thereof and moving the jet transversely of the belt a distance 40 not greater than its width during a travel of said belt throughout its entire length and simultaneously subjecting the felt through which said fluid has been forced at all times during the reconditioning operation to the 45 pressure of air throughout the entire width thereof which is to have fluid forced therethrough to cause the fluid to return through the felt, whereby the relative locations of the threads of the felt are changed.
  - 50 2. The method of reconditioning the transporting felt belts of paper making and similar machines which consists in forcing a jet of fluid and a jet of steam through a felt belt while the belt is moving longitudinally thereof and in moving the jet of fluid and the jet of steam transversely of the belt a distance not greater than the width of said jet of fluid during a travel of said belt throughout its entire length and simultaneously subjecting the felt at all 55 times during the reconditioning operation and throughout the entire width thereof which is to have fluid forced therethrough to the pressure of air to cause the fluid to return through the felt, whereby the relative 60 locations of the threads of the felt are changed.
  3. The method of reconditioning the transporting felt belts of paper making and similar machines which consists in forcing a jet of fluid through a felt belt while the belt is moving longitudinally thereof and moving the jet transversely of the belt a distance not greater than its width during a travel of said belt throughout its entire length and simultaneously subjecting the felt at all times during the reconditioning operation and through which said fluid has been forced to suction throughout the entire width thereof which is to have fluid forced therethrough to cause the fluid to return through the felt, whereby the relative locations of the threads of the felt are changed.
  - 75 4. The method of reconditioning the transporting felt belts of paper making and similar machines which consists in forcing a jet of fluid and a jet of steam through a felt belt while the belt is moving longitudinally thereof and in moving the jet of fluid and the jet of steam transversely of the belt a distance not greater than the width of said jet of fluid during a travel of said belt throughout its entire length and simultaneously subjecting the felt at all times during the reconditioning operation and through which said fluid has been forced to suction throughout the entire width thereof which is to have fluid forced therethrough to cause the fluid to return through the felt, whereby the relative locations of the threads of the felt are changed.
  - 80 5. An apparatus for reconditioning the transporting felt belt of a paper making machine having, in combination, a reconditioning member provided with a fluid ejecting port, a stationary suction member provided with a fluid suction port, means to supply fluid under pressure at said fluid ejecting port, means to apply suction at said suction port, mechanism adapted to move a transporting felt band longitudinally thereof with one face closely adjacent to said fluid ejecting and suction ports and mechanism to move said reconditioning member and its ejecting port transversely across said belt a distance approximately not greater than the distance across said fluid ejecting port during a travel of said belt throughout its entire length.
  - 90 6. An apparatus for reconditioning the transporting felt belt of a paper making machine having, in combination, a reconditioning member provided with a fluid ejecting port, a stationary suction member provided with a fluid suction port, means to supply fluid under pressure at said fluid ejecting port, means to apply suction at said suction port, mechanism adapted to move a transporting felt band longitudinally thereof with one face closely adjacent to said fluid ejecting and suction ports and mechanism to move said reconditioning member and its ejecting port transversely across said belt a distance approximately not greater than the distance across said fluid ejecting port during a travel of said belt throughout its entire length.
  - 95 7. An apparatus for reconditioning the transporting felt belt of a paper making machine having, in combination, a reconditioning member provided with a fluid ejecting port, a stationary suction member provided with a fluid suction port, means to supply fluid under pressure at said fluid ejecting port, means to apply suction at said suction port, mechanism adapted to move a transporting felt band longitudinally thereof with one face closely adjacent to said fluid ejecting and suction ports and mechanism to move said reconditioning member and its ejecting port transversely across said belt a distance approximately not greater than the distance across said fluid ejecting port during a travel of said belt throughout its entire length.
  - 100 8. An apparatus for reconditioning the transporting felt belt of a paper making machine having, in combination, a reconditioning member provided with a fluid ejecting port, a stationary suction member provided with a fluid suction port, means to supply fluid under pressure at said fluid ejecting port, means to apply suction at said suction port, mechanism adapted to move a transporting felt band longitudinally thereof with one face closely adjacent to said fluid ejecting and suction ports and mechanism to move said reconditioning member and its ejecting port transversely across said belt a distance approximately not greater than the distance across said fluid ejecting port during a travel of said belt throughout its entire length.
  - 105 9. An apparatus for reconditioning the transporting felt belt of a paper making machine having, in combination, a reconditioning member provided with a fluid ejecting port, a stationary suction member provided with a fluid suction port, means to supply fluid under pressure at said fluid ejecting port, means to apply suction at said suction port, mechanism adapted to move a transporting felt band longitudinally thereof with one face closely adjacent to said fluid ejecting and suction ports and mechanism to move said reconditioning member and its ejecting port transversely across said belt a distance approximately not greater than the distance across said fluid ejecting port during a travel of said belt throughout its entire length.
  - 110 10. An apparatus for reconditioning the transporting felt belt of a paper making machine having, in combination, a reconditioning member provided with a fluid ejecting port, a stationary suction member provided with a fluid suction port, means to supply fluid under pressure at said fluid ejecting port, means to apply suction at said suction port, mechanism adapted to move a transporting felt band longitudinally thereof with one face closely adjacent to said fluid ejecting and suction ports and mechanism to move said reconditioning member and its ejecting port transversely across said belt a distance approximately not greater than the distance across said fluid ejecting port during a travel of said belt throughout its entire length.
  - 115 11. An apparatus for reconditioning the transporting felt belt of a paper making machine having, in combination, a reconditioning member provided with a fluid ejecting port, a stationary suction member provided with a fluid suction port, means to supply fluid under pressure at said fluid ejecting port, means to apply suction at said suction port, mechanism adapted to move a transporting felt band longitudinally thereof with one face closely adjacent to said fluid ejecting and suction ports and mechanism to move said reconditioning member and its ejecting port transversely across said belt a distance approximately not greater than the distance across said fluid ejecting port during a travel of said belt throughout its entire length.
  - 120 12. An apparatus for reconditioning the transporting felt belt of a paper making machine having, in combination, a reconditioning member provided with a fluid ejecting port, a stationary suction member provided with a fluid suction port, means to supply fluid under pressure at said fluid ejecting port, means to apply suction at said suction port, mechanism adapted to move a transporting felt band longitudinally thereof with one face closely adjacent to said fluid ejecting and suction ports and mechanism to move said reconditioning member and its ejecting port transversely across said belt a distance approximately not greater than the distance across said fluid ejecting port during a travel of said belt throughout its entire length.
  - 125 13. An apparatus for reconditioning the transporting felt belt of a paper making machine having, in combination, a reconditioning member provided with a fluid ejecting port, a stationary suction member provided with a fluid suction port, means to supply fluid under pressure at said fluid ejecting port, means to apply suction at said suction port, mechanism adapted to move a transporting felt band longitudinally thereof with one face closely adjacent to said fluid ejecting and suction ports and mechanism to move said reconditioning member and its ejecting port transversely across said belt a distance approximately not greater than the distance across said fluid ejecting port during a travel of said belt throughout its entire length.
  - 130 14. An apparatus for reconditioning the transporting felt belt of a paper making machine having, in combination, a reconditioning member provided with a fluid ejecting port, a stationary suction member provided with a fluid suction port, means to supply fluid under pressure at said fluid ejecting port, means to apply suction at said suction port, mechanism adapted to move a transporting felt band longitudinally thereof with one face closely adjacent to said fluid ejecting and suction ports and mechanism to move said reconditioning member and its ejecting port transversely across said belt a distance approximately not greater than the distance across said fluid ejecting port during a travel of said belt throughout its entire length.

port, means to apply suction at said suction port, mechanism adapted to move a transporting felt band longitudinally thereof with one face closely adjacent to said fluid 5 ejecting and suction ports and mechanism to move said reconditioning member and its ejecting port transversely across said belt and alternately in opposite directions a distance approximately not greater than the 10 distance across said fluid ejecting port during a travel of said belt throughout its entire length:

7. An apparatus for reconditioning the transporting felt belt of a paper making machine having, in combination, a reconditioning member provided with a fluid ejecting port, a stationary suction member extending entirely across said belt and provided with a suction portion, means to supply 15 fluid under pressure at said fluid ejecting port, means to apply suction at said suction port, mechanism adapted to move a transporting felt band longitudinally thereof with one face closely adjacent to said 20 ejecting and suction ports and mechanism adapted to move said reconditioning member and its port transversely across said belt a distance approximately not greater than the distance across said fluid ejecting port 25 during a travel of said belt throughout its entire length.

8. An apparatus for reconditioning the transporting felt belt of a paper making machine having, in combination, a reconditioning member provided with a fluid ejecting 30 port and a heated fluid ejecting port adjacent to said fluid ejecting port, a stationary suction member provided with a fluid suction port extending transversely of said belt, 35 means to supply fluid under pressure to said 40

fluid ejecting port, means to apply heated fluid under pressure at said heated fluid ejecting port, means to apply suction at said suction port, mechanism adapted to move a transporting felt band longitudinally thereof with one face closely adjacent to said 45 ejecting and suction ports and mechanism to move said reconditioning member and its ports transversely across said belt and alternately in opposite directions. 50

9. An apparatus for reconditioning the transporting felt belt of a paper making machine having, in combination, a reconditioning member provided with a fluid ejecting port and a heated fluid ejecting port adjacent to said fluid ejecting port, a stationary suction member provided with a fluid suction port extending transversely of said belt, means to supply fluid under pressure to said fluid ejecting port, means to apply 55 heated fluid under pressure at said heated fluid ejecting port, means to apply suction at said suction port, mechanism adapted to move a transporting felt band longitudinally thereof with one face closely adjacent to said 60 ejecting and suction ports and mechanism to move said reconditioning member and its ports transversely across said belt and alternately in opposite directions a distance approximately not greater than the distance 65 across said fluid ejecting port during a travel of said belt throughout its entire length. 70

In testimony whereof I have hereunto set my hand in presence of two subscribing witnesses.

FREDERICK W. VICKERY.
